Design No. 15,001, dated May 13, 1884.

UNITED STATES PATENT OFFICE.

LOUISE TULLY, OF NEW YORK, N. Y., ASSIGNOR TO THE BUTTERICK PUBLISHING COMPANY, (LIMITED,) OF SAME PLACE.

DESIGN FOR A LADY'S WALKING-SKIRT.

SPECIFICATION forming part of Design No. 15,001, dated May 13, 1884.

Application filed March 27, 1884. Term of patent 3½ years.

To all whom it may concern:

Be it known that I, LOUISE TULLY, of the city, county, and State of New York, have invented and produced a new and original Design for a Pattern of a Lady's Walking-Skirt, (numbered 9,155,) and I do hereby declare that the engraved prints accompanying this specification convey to any one accustomed to using paper patterns a clear understanding of how a garment made up by the pattern will appear.

The design shows a round walking-skirt that exhibits a deep center front-drapery, oval at the lower edge and displaying gatherings in its back edges; deep, broad side-pan-

els; a short tablier-drapery exhibiting gatherings in its back edges; and a deep, square back-drapery that displays draping plaits in its front edges and loopings at the center.

What I claim as my invention, and desire to secure by Letters Patent, is—

The design for a lady's walking-skirt, as shown in the engraved prints accompanying this specification.

LOUISE TULLY.
